UNITED STATES PATENT OFFICE.

JOHN EDWARD THORNTON, OF WEST HAMPSTEAD, LONDON, ENGLAND, ASSIGNOR TO
JOHN OWDEN O'BRIEN, OF MANCHESTER, ENGLAND.

PHOTOGRAPHIC-PRINTING PROCESS.

1,408,315.

Specification of Letters Patent. Patented Feb. 28, 1922.

No Drawing. Original application filed March 21, 1916, Serial No. 85,702. Divided and this application filed July 8, 1919. Serial No. 309,428.

To all whom it may concern:

Be it known that I, JOHN EDWARD THORNTON, a British subject, residing at West Hampstead, London, England, have invented certain new and useful Improvements in and Relating to Photographic-Printing Processes, of which the following is a specification.

This invention relates to the production 10 of kinematograph films.

The object of the invention is to prepare a printing belt or belts by which transparent kinematograph films of continuous length can be produced by mechanical printing of 15 the pictures thereon with applied inks or colours, as distinct from printing photographically with sensitive chemical media acted upon by light, and as distinct from applying colour to a photographically 20 printed series of pictures.

The original picture film of continuous indefinite length is photographed in the ordinary way, and from this the one or more printing belts are prepared by one of the 25 processes known in photo-mechanical printing as reversed collotype, reversed hydrotype or reversed pinatype in which the fine dots, lines or other screen markings consist of a spongy porous absorbent medium, into 30 which an aqueous or spirituous ink or colour is absorbed and from which it can be subsequently transferred to the surface of the transparent kinematograph film of continuous length by the pressure of the printing 35 belt thereon.

Photo-mechanical printing is defined as follows:—The actual operation of printing requires neither the use of a sensitive surface nor the action of light, nor subsequent 40 development. Instead of such methods printing is effected by mechanical pressure of the film against a plate (in the form of a continuous belt) which has been prepared with a series of images by one of the photo- 45 mechanical processes.

The medium used to form the image is therefore a printing or applied ink or colour of aqueous or spirituous character instead of a sensitive salt. Various kinds of inks 50 or colours can be used according to the particular type of engraved or other printing plate (herein termed "printing belt") used.

I prepare a strip or band of copper, steel, brass, aluminium or other metal, or a strip

of gelatine, the gelatine being on a support- 55 ing base, or a strip of celluloid with a coating of gelatine or other colloid, prepared with a sensitive surface in any of the methods well known for photo-mechanical printing to receive an impression of the original picture 60 film.

The prepared strip which is to form the printing belt is perforated or notched along its margins or centre to correspond precisely with the perforations or notches in the camera film and in the transparent kinematograph film of continuous indefinite length. 65

Upon the prepared strip I prepare a mechanical printing surface (hereinafter referred to as a printing belt) comprising a 70 surface having a spongy porous character divided into a number of broken tone markings of fine dots, lines or other screen markings which will absorb watery or spirituous ink, and interspersed with hardened parts 75 which will not absorb the ink.

The gradations of light and shade are produced by varying the areas of the spongy or absorbent dots or lines.

In preparing printing belts from the original picture film, more particularly of the individual elemental colours, two or more of such printing belts may be made from each, one lightly exposed for the dense parts and the other fully exposed for the lighter tones. 80 By printing from one or other of these printing belts, or from both in succession, a high degree of tint is reached and desirable or special effects for harmonizing harshness or other defects becomes practicable. Or one 90 of such printing belts may be used for printing say a light shade or tone of blue or a greenish blue, and another for printing a deep blue or a purple blue to give better effect to the colours in the picture. This 95 mode of operation is regarded as of special importance in relation to originals produced by the two-colour process.

The printing belt is made of a strip of indefinite length of metal, celluloid or other 100 material, and for the hydrotype process it is made with a bichromated gelatine image in relief, prepared by exposure to light under a negative through the celluloid backing and then developed with hot water from 105 the front, thus yielding an image in varying degrees of relief. This is then soaked in watery or spirituous ink (a solution of dye)

which is then transferred to the film by pressure maintained for a long enough period to transfer sufficient dye.

By a variation of this hydrotype principle, 5 known as pinatype, the bichromate image is not developed into relief after exposure, but after washing out the surplus bichromate the soft parts of the gelatine are dyed up instead of the hardened parts, the dye being 10 next transferred by pressure as before. In still another variation of this principle, known as the Donnisthorpe process, the hardened parts of the image are dyed.

A process for forming a printing surface 15 of actual hardened gelatine is the Leimtype of Husnik which is briefly described on pages 330 and 331 of Cassel's Cyclopædia of Photography published in 1912, and further a description is given in Husnik's British 20 Specification No. 37 of 1887. To obtain the most satisfactory results by the Leimtype process certain improvements and modifications are desirable, and these, as hereinafter described, must be regarded as a part of the 25 present invention. The film base is a flexible band of metal, celluloid or other material grooved or perforated to promote the adhesion of the gelatine with which it is coated, this coating being on one side or both, and 30 the gelatine having been sensitized and printed and treated in accordance with the Husnik method gives a grained typographic surface.

The printing belt may be prepared by the 35 reversed collotype process known as hydrotype or pinatype. This method allows of a certain amount of diffusion of the colour in the gelatine layer but does not yield extremely sharp images, and is therefore better suited for the red image and the yellow 40 image for printing over a direct cyanotype or other direct sharp photographic image than for all the three stages of a colour film. For this form of hydrotype a grained or 45 cross hatched or grooved celluloid band is desirable, the slight grain resulting therefrom tending to merge into a tone, while the graining promotes the adhesion of the gelatine layer. Grooves having vertical sides are 50 specially favourable for giving the gelatine a firm hold on the celluloid.

In an improved hydrotype process the 55 printing belt is prepared similarly to collotype, but comprises a perforated backing or foundation which acts as an ink or colour reservoir, being fed with a watery or spirituous ink or dye from behind, which therefore passes through the perforations, and through 60 the porous soft gelatine parts of the image, but not through the hardened parts, and is then transferred to the film by pressure. The picture from the original picture film is printed upon the gelatine layer which is spread over the surface of the belt and by 65 uniting with the gelatine in the slits or holes

thereby sucks up the watery ink or colour applied to the back. This front layer is treated as in the ordinary collotype process to produce a printing surface.

To secure the adhesion of the gelatine or 70 other colloid to the band, the latter may be corrugated, grooved, perforated or roughened, and the band is stamped or cut with numerous small and closely grouped slits or perforations into which the gelatine will 75 penetrate. This allows the ink or colour to be applied to the gelatine layer from the back of the band. The picture from the original picture film is printed upon the gelatine layer and treated as in the ordinary 80 collotype process to produce a printing surface.

In the preparation of the printing belts, when printing through the screen it is desirable that the screen should be moved 85 slightly—relatively to the belt—either laterally or longitudinally or both after each individual picture is exposed, so that the indentations or pits in the printing surface of the printing belt and subsequently the dots 90 or points or lines printed therefrom upon the kinematograph film will not fall in the same place in the successive pictures, and so, owing to the rapidity of projection and the persistence of vision, such dots or points will 95 not be visible on the enlargement when projected upon a sheet or screen, the pictures appearing as a full tone grainless picture.

The kinematograph film.—The strip or 100 film upon which the pictures are to be printed from the printing belts to produce the finished kinematograph film may be of the ordinary celluloid material now employed for kinematograph films or any other transparent film material.

Mechanical printing of kinematograph films.—In the mechanical printing of the 105 films from the printing belts herein described any suitable printing ink of a watery or spirituous description or one containing glycerine, and all containing dye or other similar dissolved colours (other than particles of pigment) may be employed that is adapted to the particular form of printing belt and the surface of the film upon which 110 the print is to be made.

The printing may be done by applying the ink to the printing belts by any well known 115 printing method such as by rollers applying it to the face, or by rollers or damping pads applying it to the back, or by passing the belt through a trough of the watery or spirituous ink or dye.

The printing belts with perforations along 120 the margins in which registering pins can operate, and the film also similarly perforated along the margins, are drawn together 125 between rollers or pressing surfaces by which contact or pressure will be applied picture by picture. Sprocket teeth or claws 130

are fitted to draw the two through the machine in correct register.

What I claim as my invention and desire to protect by Letters Patent is:—

- 5 1. A porous photo-mechanical printing belt for the production of continuous indefinite lengths of kinematograph positive film pictures, provided with perforations and a series of printing clichés formed on the 10 surface, and having pictures arranged in succession longitudinally thereon, each cliché being capable of printing a half-tone image with all the gradation of a photograph by planographic methods; the cliché consisting 15 of a large number of broken tone markings, of a spongy character, capable of absorbing an ink, and from whence it is capable of being transferred to the film to be printed by means of applied pressure, and the interspaces 20 between these broken tone markings representing the whites of the picture consisting of non-porous material which cannot absorb the ink; and the gradation of image being formed by making the said printing broken tone markings of varying size and area so that they are capable of depositing varying areas of ink, and thus forming a 25 series of printed images of full gradation by the agency of applied ink and pressure.
- 30 2. A porous photo-mechanical printing belt for the production of continuous indefinite lengths of kinematograph positive film pictures, provided with perforations and a series of printing clichés formed on the 35 surface and having pictures arranged in succession longitudinally thereon, each cliché being capable of printing a half-tone image with all the gradation of a photograph by planographic methods; the cliché consisting 40 of a large number of broken tone markings of a spongy character, through which the ink can percolate from the back of the belt to the front printing surface, and from whence it is capable of being transferred to 45 the film to be printed by means of applied pressure, and the interspaces between these broken tone markings representing the whites of the picture consisting of non-porous material through which the ink cannot 50 penetrate; and the gradation of image being formed by making the said printing broken tone markings of varying size and area so that they are capable of depositing varying areas of ink, and thus forming a series of 55 printed images of full gradation by the agency of applied ink and pressure.
3. A series of porous perforated photo-mechanical printing belts for producing continuous indefinite lengths of kinematograph positive films, as in claim 2, for printing the main part of each image by one printing belt, and intensifying parts of each image, by printing from another printing belt, the corresponding parts of each image 60 of the series being different in ink area for each belt, and requiring the printing from all belts in succession to complete the series of images and to differentially intensify each image of the series.
4. A series of perforated photo-mechanical 70 printing belts for producing continuous indefinite lengths of kinematograph positive films, by means of a large number of broken tone markings of spongy character and of varying size and area, as in claim 1, the 75 said printing points having their incidence varied in relation to the particular part of the picture image upon every printing belt of the series, in order that the grain of the picture may be obliterated by the successive printings, and thus form a series of full-tone grainless film pictures by aqueous ink applied through the back of the belt and by pressure and superimposed printings. 80
5. A series of perforated photo-mechanical 85 printing belts for producing continuous indefinite lengths of kinematograph positive prints in multi-colour heliochrome, by means of a large number of broken tone markings of spongy character and of varying size 90 and area as in claim 1, each colour of the composite heliochrome being formed upon a separate belt, which belts are subsequently printed on to the film by superimposed planographic printing, and by aqueous inks applied through the back of the belt, and by pressure, to produce complete heliochrome continuous positive films. 95
6. A series of perforated photo-mechanical 100 printing belts for producing continuous indefinite lengths of kinematograph positive prints in multi-colour heliochrome, by means of a large number of broken tone markings of spongy character and of varying size and area as in claim 1, the composite heliochrome 105 being split into a plurality of printings of each colour, and each being printed from a different belt in which the printing points have their incidence varied in relation to the same particular part of the picture image, in order that the broken tone markings of one printing may be obliterated by the second printing of the same section of the picture, with the object of producing when the remaining colours of the image series have 110 been similarly split and applied a series of grainless full-tone heliochrome kinematograph positive film pictures, by aqueous inks applied through the back of the belt and pressure and superimposed planographic 115 printings. 120
7. A continuous planographic printing belt of indefinite length as in claim 1, having its printing clichés produced by spongy broken tone markings of varying size and area, which deliver varying quantities of ink according to their varying areas, and capable of yielding it to an absorbent film surface by means of applied pressure, and also having apertures through which such 125 130

ink is applied to the back of the spongy printing belt to penetrate to the front.

8. A continuous spongy printing belt, as in claim 1 having its surface grooved to promote adhesion of the clichés formed on its face and prevent their tearing off during inking and printing.

9. A continuous planographic printing belt for direct printing on to a continuous kinematograph film, and prepared with spongy planographic images by the improved hydrotype methods as in claim 1, in which the incidence of the screen marking is varied in each succeeding picture of the series therein.

10. A photo-mechanical perforated or notched printing belt, having formed thereon by photo chemical means a series of printing clichés, each composed of a large number of spongy printing points, the gradation of each image being formed by making the said printing points of varying size and area, to render them capable of depositing varying areas of ink to form pictures, in the form of a continuous longitudinally series upon a continuous indefinite length of kinematograph film, the said inks being of an aqueous character, and applied to the film during printing through the back of the spongy printing belt, substantially as described.

11. A continuous printing belt as in claim 1, having its printing clichés produced by

planographic methods, in which some parts are non-porous, corresponding to the whites of the picture, some parts extremely porous, corresponding to the shadows of the picture, and some parts less porous corresponding to the half-tones of the picture, and formed in a series of markings of varying area, and provided with apertures filled with spongy colloid through which the printing belt is fed with inks or dyes from the back, such inks being fed through the porous portions of the belt from back to front, and transferred from the front to an absorbent film surface by applied pressure.

12. A perforated photo-mechanical continuous printing belt having planographic clichés thereon, formed with holes in its body which are filled with spongy filling that is also continued on to the back and front parts of the belt, to act as an ink feed fountain, by which aqueous ink containing colour applied to the back of the belt whilst it is moving is gradually fed through the belt to the porous portions of the clichés attached to its face, when used for planographic processes.

In testimony whereof I have hereunto set my hand in presence of two subscribing witnesses.

JOHN EDWARD THORNTON.
